UNITED STATES PATENT OFFICE.

CHESTER B. ALBREE, OF ALLEGHENY, PENNSYLVANIA.

BOLSTER.

SPECIFICATION forming part of Letters Patent No. 733,791, dated July 14, 1903.

Application filed March 20, 1903. Serial No. 148,723. (No model.)

To all whom it may concern:

Be it known that I, CHESTER B. ALBREE, of Allegheny, in the county of Allegheny and State of Pennsylvania, have invented a new and useful Bolster, of which the following is a full, clear, and exact description, reference being had to the accompanying drawings, forming part of this specification, in which—

Figure 1 is a side elevation showing one form of my improved bolster. Fig. 2 is an end elevation of the same. Fig. 3 is a cross-section on the line III III of Fig. 1. Fig. 4 is an end elevation of a modified form with the flanges reversed. Fig. 5 is a side elevation of a modified form with end tie-plates. Fig. 6 is an end elevation of the form of Fig. 5, and Figs. 7 and 8 are end elevations showing other modifications.

My invention relates to the class of bolsters for railway-cars and car-trucks, especially the latter, and is designed to provide a bolster which may be formed of commercial rolled shapes or sections and plates without the necessity of any flanging or pressing up of special shapes. It is also designed to provide such a bolster wherein all the rivets may be driven by horseshoe-yoke compression-riveters to avoid the expense of hand-riveting with internal dolly-bars and at the same time to obtain a bolster of great strength by making it deeper at the center than at the ends.

In the drawings, referring to the form of Figs. 1, 2, and 3, I show the bolster as formed of an upper pair of Z-bars 2, with their upper flanges 3 projecting outwardly and their lower flanges 4 projecting inwardly, and a lower pair of Z-bars 5, with their upper flanges 6 projecting inwardly and registering with the flanges 4 and with their lower flanges 7 projecting outwardly and riveted or otherwise secured to the lower tension member or cord 8. This lower cord consists of a plate of rectangular form, which is bent or curved downwardly in its intermediate portion to conform to the downwardly bent or curved intermediate portions of the lower Z-bars 5. The end portions of the flanges 4 and 6 fit against and are riveted to each other within the bolster. Between these points the lower Z-bars are bent downwardly, as shown in Fig. 1, and at the center I provide one or

more struts or columns 9, which extend between and space apart the flanges 4 and 6 at this point, being secured by long rivets 10 or other suitable means.

To the top flanges 3 of the upper Z-bars I rivet the upper cord or tension members 11, which consist of a plane rectangular plate conforming to the shape of the bolster. 60

Instead of arranging the Z-bars with their coacting flanges projecting inwardly I may reverse them, as shown in Fig. 4. In this form the upper flanges 3^a project inwardly, as do also the lower flanges 7^a, and the intermediate flanges 4^a and 6^a project outwardly in opposite directions and are riveted together, as before.

In Figs. 5 and 6 I show a form similar to that of Figs. 1, 2, and 3, except that tie-plates 70 12 are secured between the end portions of the flanges 4^b and 6^b. These tie-plates strengthen the bolster and serve as additional means for securing the Z-bars together in their end portions. Where the Z- 75 bars are used in upper and lower pairs, the upper flanges of one bar of each pair must project in the opposite direction to that of the other of the pair.

Instead of using Z-bars for forming the 80 bolster I may use other shapes. Thus in Fig. 7 I show an upper pair of channels 13, with their flanges 14 projecting outwardly, these channels resting on a similarly-arranged pair of channels 15 below them and having corresponding flanges 16. The lower pair of channels will be bent downwardly in their intermediate portions, as in the Z-bar construction, and the upper and lower cords or plates 17 and 18 are riveted to the flanges. 85 90

In Fig. 8 I show another form where two pairs of I-beams 19 and 20 are arranged in superimposed position similar to that of Fig. 7 with the upper and lower side plates 21 and 22. 95

In all of the forms the depth at the center of the bolster is increased, and this may be done by bending either one of the pairs of rolled sections or by bending both pairs in opposite directions, and I intend to cover 100 either of these constructions in my claims.

The advantages of my invention result from the strength of the bolster, for the amount of material contained, and from the ease and

cheapness with which the bolster may be made and repaired. The riveting may be cheaply and rapidly carried out by the ordinary U-shaped riveter, avoiding the use of 5 dolly-bars and hand labor. The construction adapts itself readily to either cars or car-trucks and is free from vertically-projecting flanges, which would increase the height of the bolster.

10 The rolled shapes may be varied, the means for increasing the depth at the center may be changed, and many other variations may be made in the form and arrangement of the sections and upper and lower cords without de- 15 parting from my invention.

I claim—

1. A bolster having a lower pair of rolled flanged shapes arranged side by side, and another pair of rolled flanged shapes superimposed thereon and having all parts thereof above the level of the lower pair, the depth of the bolster being greater at the center than at the end; substantially as described.

2. A bolster having a lower pair of flanged shapes arranged side by side, an upper pair of flanged shapes superimposed thereon, the end portions of the lower flanges of the upper pair resting on the upper flanges of the lower pair, the depth of the bolster being greater 25 at the center than at the ends; substantially as described.

3. A bolster having a lower pair of flanged shapes arranged side by side, an upper pair of flanged shapes superimposed thereon, the

lower flanges of the upper pair being in contact with the upper flanges of the lower pair at the end portions of the bolster and separated from them at their intermediate portion, and upper and lower plates covering the top and bottom of the bolster; substantially 35 as described.

4. A bolster having a pair of Z-bars arranged side by side with their flanges projecting in opposite directions, an upper pair of similarly - arranged Z - bars superimposed 45 thereon, the lower flanges of the upper pair resting on the upper flanges of the lower pair in the end portions, at least one of the pairs being bent or curved away from the other pair from the central portion of the bolster; 50 substantially as described.

5. A bolster having a pair of Z-bars arranged side by side with their flanges projecting in opposite directions, an upper pair of similarly - arranged Z - bars superimposed 55 thereon, the lower flanges of the upper pair resting on the upper flanges of the lower pair in the end portions, at least one of the pairs being bent or curved away from the other pair from the central portion of the bolster, 60 and a strut between the central portions of the pairs; substantially as described.

In testimony whereof I have hereunto set my hand.

CHESTER B. ALBREE.
